UNITED STATES PATENT OFFICE

JOHN L. DAWES, OF PITTSBURG, PENNSYLVANIA.

DESIGN FOR BOTTLE.

Specification forming part of Design No. **6,159**, dated October 1, 1872.

To all whom it may concern:

Be it known that I, JOHN L. DAWES, of Pittsburgh, in the county of Allegheny and State of Pennsylvania, have invented a new and useful Design for Bottles; and I do hereby declare the following to be a full, clear, and exact description thereof, reference being had to the accompanying drawing making a part of this specification, which represents my improved design for a bottle in elevation.

To enable others skilled in the art to make and use my improved design I will proceed to describe the same.

It consists of a bottle, or other like article of glass-ware, made in imitation of a dog, the body and legs being represented in the body of the bottle, and the neck and head in the neck of the bottle.

The body of the bottle in the drawing shows the body of a dog, except that a label face or seat, *a*, may be made on the belly. The legs are shown at *b*, the tail at *c*, the ears at *e*, and the mouth at *f*, holding between the open jaws the bottle-mouth *g*. The face of the bottle is made in imitation of hair.

What I claim as my improved design, and desire to secure by Letters Patent, is—

The design, substantially as set forth and shown.

In testimony whereof I, the said JOHN L. DAWES, have hereunto set my hand.

JOHN L. DAWES.

Witnesses:

WILLIAM F. ROBB,
G. H. CHRISTY.
